MICROSCOPE

John C. Kurtz, Irondequoit, N. Y., assignor to
Bausch & Lomb Optical Company, Rochester,
N. Y., a corporation of New York

Application July 23, 1948, Serial No. 147,724

Term of patent 14 years

(Cl. D57—1)

To all whom it may concern:

Be it known that I, John C. Kurtz, a citizen of the United States and a resident of the town of Irondequoit, county of Monroe, and State of New York, have invented a new, original, and ornamental Design for a Microscope, of which the following is a specification, reference being had to the accompanying drawing, forming a part hereof.

Fig. 1 is a perspective view of a microscope, showing my new design.

Fig. 2 is a fragmentary perspective view of the microscope taken from a side thereof.

The essential features of my design reside in the parts shown in full lines and include the integrally formed body tube and nosepiece which are merged as shown.

I claim:

The ornamental design for a microscope, substantially as shown and described.

JOHN C. KURTZ.
